WATER HEATER CONTROL SYSTEM

Clark M. Osterheld, Stoughton, Wis., assignor to
McGraw Electric Company, Elgin, Ill., a cor-
poration of Delaware

Application March 20, 1944, Serial No. 527,301

4 Claims. (Cl. 218—39)

My invention relates to electric heating and particularly to control systems for hot water tank heaters.

An object of my invention is to provide a system for controlling the electric heater of a domestic hot water tank adapted to be energized during night hours to ensure that all of the water in the tank shall be hot before the heater is deenergized.

Another object of my invention is to provide a heater control system adapted to energize an electric heater during night hours only and that shall ensure continuation of energization of the heater beyond the night hours in case less than all of the water in the tank is hot when daylight comes on.

Other objects of my invention will either be apparent from a description of one form of control system embodying my invention or will be pointed out in the course of such description and set forth particularly in the appended claims.

In the drawing,

Figure 1 is a view in vertical section through a domestic hot water tank having associated therewith a control system embodying my invention,

Fig. 2 is a diagram of connections embodying my invention, and,

Fig. 3 is a fragmentary diagram of connections showing somewhat different parts.

Referring to Fig. 1 of the drawing, I have there illustrated a usual domestic hot water tank 11 having a lower cold water inlet pipe 13, an upper hot water outlet pipe 15, heat-insulating material 17 around the tank, which latter may be held in proper operative position relative to the tank 11 by an outer casing 19.

I provide preferably, but not necessarily, a single electric heater 21, which, if only a single electric heater is used, is located near the lower end of the tank. I have illustrated a clamp-on electric heater preferably located in a tunnel 23. All of these hereinabove described parts are old and well known in the art and constitute no part of my present invention.

Referring now to Fig. 2 of the drawing, I have there illustrated one diagram of connections embodying my invention as used to control the electric heater 21. I provide a lower main thermally-actuable heater control switch 25 which is illustrated generally or schematically only as comprising a bimetal bar 27, having one end thereof fixed on a contact member 29, while the other free end thereof is adapted to be engaged with and disengaged from a second fixed contact

member 31, to which one end of the electric heater 21 is connected.

I provide also a thermal retarder designated as an entity by numeral 33 and which is disclosed and claimed in my co-pending application, S. N. 511,387, filed November 22, 1943, and assigned to the same assignee as is the present application. This thermal retarder includes a heat-conducting support 35, which is preferably secured to the outside of the tank 11 at substantially the mid-height thereof. It includes further a high expansion rod 37, mounted on the support 35, and a low expansion rod 39, supported by supporting member 35 with a block 41 of heat-insulating material disposed therebetween to render the flow of heat from heat-conducting support 35 to low expansion member 39, as small as possible. The thermal retarder 33 includes further a switch contact arm 43, which is of substantially L-shape and is supported at two points thereof by rods 37 and 39. The switch contact part of member 43 is adapted to engage with and be disengaged from two fixed contact members 45 and 47.

When the support 35 is subject to the temperature of cold water in the tank, that is either when the tank is first filled with cold water, or becomes filled with cold water during normal operation thereof, the length of expansion rod 37 will be a minimum. By cold water I mean water which has a temperature on the order of 65° to 70° F., or slightly less. When the length of expansion rod 37 is a minimum and the temperature of the low expansion rod 39 is that of the ordinary room, on the order of 70° F., the switch member portion of member 43 will be in engagement with contact members 45 and 47. If now, because of energization of heater 21 for a length of time sufficient to cause the temperature of the water in the tank to approach a predetermined maximum value on the order of 150° F., the temperature of rod 37 will also be on the order of 150° F. with the result that, if expansion rod 39 is still at ordinary room temperature, or only slightly thereabove, the bridging member 43 will be disengaged from contact members 45 and 47.

I provide further a low wattage heating coil 49 operatively associated with the low expansion rod 39, which heating coil, when energized for a length of time on the order of four to six hours, will cause an increase in the temperature of rod 39 to a value on the order of 300° F. and resultant expansion longitudinally of rod 39, with the result that even though expansion rod 37 is heated because of being subject to hot water in the tank, the position of switch arm 43 will be again in en-

gagement with contacts 45 and 47. In order to vary the length of time required for heating coil 49, when energized, to cause temperature rise of expansion rod 39 to a value on the order of 300° F., I may provide an adjustable rheostat 51, which may be adjusted as may be found desirable or necessary.

I provide a light-sensitive device 53, shown in Fig. 2 as being a selenium cell, which cell has the property of being non-conducting when dark and being conducting when subject to daylight or other artificial light. I am particularly interested in so arranging cell 53 that it is subject to daylight.

An electromagnetic heater control switch 55 is controlled by cell 53 and includes an upper electromagnetic core 57, a lower electromagnetic core 59, and a contact bridging member 61 carried and movable with the two cores 57 and 59. The upper core 57 is provided with a coil 63, which is adapted to be traversed by a coil passing through selenium cell 53 during daylight hours. Contact bridging member 61 is adapted to be engaged with and disengaged from a pair of fixed contact members 67 and 69. I provide a pair of supply circuit conductors 71 and 73, one terminal of cell 53 being connected to the first supply circuit conductor 71, while the other terminal of cell 53 is connected to one terminal of coil 63, the other terminal of coil 63 being connected by a conductor 75 to the second supply circuit conductor 73. The second supply circuit conductor 73 is connected by a conductor 77 to fixed contact 29 of the thermally-actuable switch 25. The other terminal of heater 21 is connected by a conductor 79 to contact 47. The second contact 31 of heater control switch 25 is connected, as has already been stated, to one terminal of heater 21 and by a conductor 81 to one terminal of the adjustable rheostat 51, while the other terminal of rheostat 51 is connected by a conductor 83 with one terminal of heating coil 49, the other terminal of which is connected by a conductor 85 to contact 45.

The lower electromagnetic armature core 59 is provided with a coil 87, one terminal of which is connected by a conductor 89 to contact 45, while the other terminal of coil 87 is connected by a conductor 91 with fixed contact 67 of the electromagnetic switch 55. The other contact 69 is connected by a conductor 93 with the first supply circuit conductor 71. It may here be pointed out that coil 63 is a coil of relatively fine wire having a relatively large number of turns in order to provide the necessary effect upon electromagnetic armature core 57, when traversed by a current flowing through cell 53, namely to cause disengagement between contact bridging member 61 and the fixed contacts 67 and 69. Coil 87 is made of relatively heavy wire, since it is adapted to be traversed by the current flowing through heater 21.

It is evident that with the location of cell 53 such that it will be subject to daylight, current will flow through cell 53 shortly after sunrise, with the result of raising of the two armature cores 57 and 59 to cause disengagement of contact bridging member 61 from the fixed contacts 67 and 69. The heater circuit will therefore be opened, particularly so if substantially all of the water in the tank was heated during the hours of darkness, so that bimetal bar 27 was moved away from engagement with fixed contact 31 before daybreak.

If, however, because of demand for and use of hot water during late night hours, with the result that cold water entered the tank, say to a point

above the position of the thermal retarder 33, with the result that the thermal retarder was subject to cold water with attendant engagement of switch member 43 with contacts 45 and 47, energization of heater 21 would have been effected, since bimetal bar 27 would also be subject to cold water. The circuit of heater 21 will be traceable substantially as follows: from supply circuit conductor 73 through conductor 71, main thermal switch 25, heater 21, conductor 79, through closed switch of the thermal retarder 33, that is contact 47, switch arm 43, contact 45, conductor 89 and coil 87, conductor 81, contacts 67 and 69, and bridging member 61, and through conductor 83 to the other supply circuit conductor 71. This is made possible by reason of the fact that cell 53, being in darkness, will be non-conducting so that normally contact bridging member 61 will be in engaged position relatively to contacts 67 and 69. It has already been assumed that a relatively large amount of cold water is in tank 11, and this amount is so great that all of the water in the tank will not be hot by daybreak. The design of coil 87 is such that it will overcome the tendency of coil 63, traversed by current flowing through cell 53 after daybreak, to raise the contact bridging member 61 upwardly and out of engagement with contacts 67 and 69 and will keep contact bridging member 61 in engagement with contacts 67 and 69, the result being that energization of heater 21 will continue until substantially all of the water in the tank is hot, when main thermal switch 25 will open the circuit.

Let it be assumed that the amount of cold water in tank 11 is not as great as in the above example and that the bimetal bar 27 was moved into engagement with contact 31 at a time, say on the order of five hours, before daybreak. Closure of the main thermal switch 25 would cause energization of heating coil 49, with the result that the temperature of the low expansion member 39 would be raised to a value on the order of 300° F., just before daybreak, with the result that the thermal retarder heater control switch would be moved to closed position to establish the hereinbefore mentioned energizing support for heater 21, with the result that even though cell 53 would be traversed by a current after daybreak, the electromagnetic switch 55 would not be moved to open position until substantially all of the water in the tank was heated to a predetermined high temperature, when switch 25 would be moved to open position to deenergize the system.

It is obvious that with opening of the electromagnetic switch 55, when substantially all of the water in the tank has been heated to a predetermined high temperature, the contact bridging member 61 would be moved upwardly out of engagement with its cooperating contacts so that the entire control system would be deenergized for the rest of the daylight hours.

Referring now to Fig. 3, I have there illustrated a modification of my control system in which a photo-electric cell or bulb 95 is used, this bulb being of the kind adapted to generate an electric current when subjected to daylight. The coil 63 is connected to the terminals of bulb 95 and is adapted to be positioned around the upper end of an elongated electromagnetic armature core 97. The core 97 is adapted to actuate a contact bridging member 99 into and out of engagement with fixed contact members 101 and 103. Contact member 103 is connected to supply circuit conductor 71 as by a conductor 93. Contact 101 is connected by a conductor 105 to one

terminal of coil 87 positioned around the lower end of core 97, the other end of coil 87 being connected by a conductor 107 with contact member 45 of the thermal retarder switch 33.

It will be evident that the operation of the control system, part of which is shown in Fig. 3, to replace like parts in the system shown in Fig. 2, will be substantially the same as that set forth in the description of Fig. 2.

I may point out also that while I have shown a direct connection between the selenium cell 53 and coil 63, it is within the province of my invention to interpose a relay designed to control a secondary circuit, including coil 63, and the same remarks apply as to the diagram of connections shown in Fig. 3.

It is the rule in some utilities supplying electric energy for light, heat, and power, to require that water heaters be disconnected from their circuits during daylight hours, and this makes it desirable, even necessary, to ensure that those few installations of electric water heaters which experience extra heavy demands for hot water during late night hours shall be controlled so that the tank is full of hot water before the heater is finally disconnected from the supply circuit. It is obvious further that the control systems shown in Figs. 2 and 3 of the drawing will accomplish such object and that they employ a minimum number of component and cooperative elements in attaining such object.

Various modifications may be made in the system embodying my invention without departing from the spirit and scope thereof, and all such modifications coming clearly within the scope of the appended claims are to be considered a part of my invention.

I claim as my invention:

1. A water heater control system for a hot water tank having an electric heater, said system comprising a first thermal heater control switch subject to tank water temperature at the lower end of the tank, a thermal retarder switch unit mounted on the tank intermediate the ends thereof and including a first expansion member subject to tank water temperature, a second expansion member out of close thermal communication with said tank, a heating coil for said second expansion member and a second heater control switch connected in series circuit with said first heater control switch, a third heater control switch connected in series circuit with said other two heater control switches, a light sensitive means effective to hold said third heater control switch in open position during daylight hours and means to cause prolongation of the energization of the heater beyond the start of daylight hours in case less than all of the water in the tank is hot at that time, said means comprising heater-current controlled means for holding said third heater control switch in closed position until deenergization of the heater by said first thermal heater control switch.

2. A water heater control system for a hot water tank having an electric heater, said system comprising a first thermal heater control switch effective to deenergize said heater when substantially all of the water in the tank is hot, a second daylight-controlled heater control switch effective to deenergize said heater when daylight starts, a thermal retarder switch unit comprising a pair of expansion members, one of which is subject to tank water temperature intermediate the ends of the tank and the second of which is

provided with a heating coil, the energization of which is controlled by said first and second switches and a third heater control switch in series circuit with said other two switches, said

5 thermal retarder switch unit being effective to cause closure of its switch and energization of said heater with a preset time period of delay after start of darkness in case of use of only a relatively small amount of hot water from the 10 tank and means to cause prolongation of the energization of said heater beyond the start of daylight hours in case less than all of the water in the tank is hot at that time, said means comprising heater-current controlled means for holding said second heater switch in closed position until deenergization of said heater by said first thermal heater control switch.

20 3. A water heater control system for a hot water tank having an electric heater, said system comprising a first thermal heater control switch 25 on the tank subject to tank water temperature at the lower end thereof effective to deenergize said heater when substantially all of the water in the tank is hot, a second daylight-controlled heater control switch including a coil adapted to carry current during daylight hours to hold said second switch in open position and a heater-current carrying coil on said second switch adapted to hold it in closed position after start of daylight 30 hours in case energization of said heater during night hours has heated less than all of the water in the tank before the start of daylight hours, said first switch being effective to cause deenergization of the heater when substantially all of the water in the tank is hot.

35 4. A water heater control system for a hot water tank having an electric heater, said system comprising a first thermal heater control switch 40 on the tank subject to tank water temperature at the lower end thereof effective to deenergize said heater when substantially all of the water in the tank is hot, a second heater-control switch of the electromagnetic type in series circuit with said first switch and including a coil, a light-sensitive device for causing said coil to be traversed by a current during daylight hours to hold the switch in open position to deenergize said heater during daylight hours, a third heater control switch unit in series circuit with said heater 45 and said first and second heater-control switches and including a first thermally-expansible member subject to tank water temperature at a portion intermediate the ends thereof, a second thermally-expansible member out of close thermal 50 communication with the tank water temperature, a heating coil for said second thermally-expansible member controlled jointly by said first and second heater control switches, said third heater control switch being adapted to be closed immediately after nightfall in case the tank contains enough cold water to affect said first thermally-expansible member and to be closed with an adjustably preset time period of delay after 55 nightfall in case the tank contains only enough cold water to affect said first heater control switch and a heater-current traversed coil on said second heater control switch adapted to hold said second switch in closed position after start of daylight hours in case less than all of the water in the tank is hot at the start of daylight hours, said first thermal heater control switch effecting deenergization of the heater when substantially all of the water in the tank is hot.

CLARK M. OSTERHELD.
